United States Patent Office.

JOSEPH N. ARONSON, OF NEW YORK, N. Y.

Letters Patent No. 95,966, dated October 19, 1869.

REFLECTOR FOR STREET-LAMP.

The Schedule referred to in these Letters Patent and making part of the same.

To all whom it may concern:

Be it known that I, JOSEPH N. ARONSON, of the city, county, and State of New York, have invented a new and useful Improvement in Reflectors for Street-Lamps; and do hereby declare that the following is a general description thereof, reference being had to the accompanying drawings, making part of this specification, of which—

Figure 1 represents a perspective view of the street-lamp, with my invention applied to it;

Figure 2, a top view of the reflector, on an enlarged scale, removed from the lamp; and

Figure 3, end view of same.

The nature of my invention consists in the particular construction and arrangement of two or more corrugated-glass or transparent reflectors on a suitable frame-work applied to a street-lamp, for the purpose of concentrating, multiplying, and throwing the reflected and transmitted light in opposite directions, by means of which a greater volume of light can be obtained from the same amount of gas or oil, and a consequent saving of these illuminating-agents effected.

In the said drawings—

A indicates an ordinary street-lamp, provided with a gas-burner, B, in the usual manner.

C C are the glass or transparent reflectors, which also serve as lenses to transmit and converge a portion of the light, which may be concavo-convex, corrugated on the outer surface, and of which there may be two or more.

These reflectors are each confined within a silver-

plated band, D, which aids in reflecting the light, while the said bands, being provided with sockets, E E, for reception of the arms F F, &c., of the frame G, sustain the reflectors at any desired angle in relation to the lamp.

These arms, F F, project from a collar, H, which embraces the neck of the burner B, and being provided with a set-screw, K, for adjustment, constitute the frame-work G for sustaining the reflectors.

The street-lamps in present use require no alteration to suit them to my device, as I merely open the door of the lamp and set the frame G, with its reflectors C C, on the neck of the burner B, and fasten the same in position by the set-screw K, close the lamp-door, when the reflectors are in action; this being but the work of a moment.

What I claim as my invention, and desire to secure by Letters Patent, is—

The arrangement of oppositely-situated lens-reflectors C C, mounted, by means of band-sockets E E, on forked arms F F, which project from a collar, H, provided with a set-screw, K, so that the whole may be applied to and adjusted on the ordinary burner of a street-lamp, substantially as and for the purpose herein specified.

In testimony whereof, I have hereunto set my signature, this 28th day of July, A. D. 1869.

JOSEPH N. ARONSON.
